SHAVING MACHINE

Norman H. Lewis, Rochester, N. Y., and Emil G. Berg, Providence, R. I., assignors of one-third to Robert Stockman, Providence, R. I.

Application July 9, 1934, Serial No. 734,244

1 Claim. (Cl. 30—48)

The object of this invention is to provide an improved shaving machine with which the hair may be shaved closer to the skin than has heretofore been possible.

Another object of this invention is to so construct the shaving machine that its cutter head may be held at various angles to the skin when shaving to facilitate an easy manipulation thereof.

10 Another object of this invention is to provide a cutter head for a shaving machine in which the guard members, as well as the cutter members, are rounded to make them rigid and self supporting and nonyielding to the pressure applied 15 against them in shaving.

Another object of this invention is to provide the cutter head with a clamping member which, in clamping the cutter head to the handle, automatically locates the guard and cutter of the 20 head and yieldingly urges the cutter against the inside of the shear plate.

Another object of this invention is to provide the cutter head of a shaving machine with rigid self supporting cutting blades which are angular 25 to the shear blades with which they cooperate.

Another object of this invention is to provide the armature shaft of the motor of the shaving machine with a file which presents a small portion 30 of its peripheral surface below the cutter head so that the fingernails may be conveniently filed and shaped therewith.

All these and other objects and attendant advantages will become more readily apparent from 35 the detailed description of the invention which follows, reference being had to the accompanying drawings in which

Figure 1 is a front elevation of the shaving machine.

40 Figure 2 is a side elevation of the shaving machine.

Figure 3 is a rear elevation of the shaving machine.

45 Figure 4 is an enlarged vertical sectional view of the upper portion of the handle of the shaving machine and the cutter head held in place thereon, the section being taken on the line 4x—4x of Figure 3.

50 Figure 5 is an enlarged vertical sectional view of the shaving machine taken on the line 5x—5x of Figure 3.

Figure 6 is an enlarged view of the rear of the upper portion of the handle of the shaving machine taken on the line 6x—6x of Figure 5.

55 Figure 7 is a horizontal sectional view of the

shaving machine taken on the line 1x—1x of Figure 5.

Figure 8 is an enlarged detail side elevation of the cutter head.

Figure 9 is a vertical sectional view of the 5 cutter head taken on the line 9x—9x of Figure 8.

Figure 10 is a top plan view of the cutter head with a portion of the guard member broken away.

In the several figures of the drawings like reference numerals indicate like parts.

The shaving machine forming the subject matter of our present invention is constructed so that its cutter head may be held at various angles against the surface of the skin without impairing the cutting operation of the cutter head, and in addition the cutter head is mounted angularly in the end of the handle to facilitate the manipulation of the shaving machine in the most convenient position.

As illustrated in the figures of the drawings, 20 the shaving machine comprises a handle 1 which is hollow and has a suitable electric motor (not shown) mounted therein for the operation of the cutter in the cutter head. In the outer end of the handle 1 is formed an angularly positioned transverse channel 2 into which the cutter head of the shaving machine is mounted. Within the handle 1 is mounted to oscillate the lever 3 which is bifurcated at one end at 4 to have the eccentric pin 5 carried by the motor shaft 6 project thereinto and oscillate the lever 3 on the rotation of the armature shaft. The free end of the oscillating lever 3 carries the lug 7 which is adapted to engage the cutter of the cutter head to be reciprocated thereby.

The cutter head is made up of a guard 8 which is preferably formed up of sheet metal to provide a hollow guide member with a flat supporting base at the bottom and a rounded shear plate at the top. A hollow cutter 9, which is also preferably formed up of sheet metal and provided with a rounded top and a flat base, is mounted within the guard 8 so as to have its rounded top reciprocate below the rounded shear plate of the guard and in contact therewith.

The rounded and convexed outside of the shear plate of the guard has a larger radius than the rounded and concaved inside and the two radii are so arranged that the thickness of the shear plate gradually decreases from the sides towards the middle thereof. This makes it possible to provide the shear plate with a crown of extreme thinness which, due to its curvature, is extremely rigid and self supporting and will not 55

yield when pressure is applied against it in shaving. The shear plate is divided into a series of narrow parallel blades 10, 10 by the slits 11, 11 which are cut thru the rounded end of the guard 5 to provide the cutting edges on the under side of the shear plate.

The heavier outer ends of the blades 10, 10 of the shear plate are undercut at 12 and 13 and the sides thereof are beveled at 14 and 15 so 10 as to widen the slits 11 between the outer ends of the blades 10 and provide guide slots which gradually decrease in width to collect and guide the hair into the slits 11. When the guard is held against and moved over the skin for shaving, the surface of the skin is slightly indented by the rounded shear plate so that the under cut and outwardly projecting ends of the blades 10, 10 thereof group the hairs and guide them into the slits 11. In this way the hair to be 15 shaved is guided in parallel rows over the shear plate to project thru the thinnest portion thereof to be cut off by the cutter close to the surface of the skin.

The rounded top of the cutter 9 is yieldingly 20 held against the correspondingly rounded under side of the shear plate and is divided into a series of angular parallel cutting blades 16, 16 by slitting the rounded top of the cutter at an angle 25 to the sides thereof. The width and the arrangement, together with the length of movement of the cutting blades 16, is such that the sides thereof cooperate with the cutting edges of the blades 10 of the shear plate to clip the hair which is made to project thru the slits in the shear plate 30 with a shear cut.

For the operation of the shaving machine the cutter head is clamped to the handle by means of the pair of clamping screws 17 and 18. These screws pass thru suitable holes in the bottom of 40 the channel 2 of the handle so as to engage the threaded holes 19 in the base of the guard 8. The guard is thus firmly drawn and clamped into the mounting and held fixed therein. Each of the clamping screws 17 and 18 also carries a 45 spring pressed extension pin 20 of reduced diameter and the outer ends of these extensions project thru the holes 19 and yieldingly rest against the base of the cutter 9 so as to constantly and yieldingly urge the rounded top of this cutter 50 against the rounded bottom of the shear plate 8.

When the guard of the cutter head is clamped to the handle, the lug 7 of the oscillating lever 3

projects thru the opening 21 in the base of the guard to engage into the transverse groove 22 provided in the bottom of the cutter. The oscillating lever is thus automatically connected to the cutter so that on the oscillation thereof by 5 the motor in the handle, the cutter is rapidly reciprocated within the guard to perform its cutting operation.

As heretofore pointed out, the rounding of the shear plate increases its rigidity to the extent 10 so that its thickness may be reduced to a minimum so that the skin over which the shaving machine is drawn may enter the slits in the shear plate 15 to a point where the cutting blades of the cutter will sever the hair substantially next to the skin without cutting into the skin.

The motor used for operating the shaving machine is not a self starting motor and for this reason a starting wheel 23 is mounted on the armature shaft 6. A small portion of the periphery of this starting wheel is made to project from one or both sides of the handle 4 so that it can be turned to start the motor. The starting wheel serves another useful function by providing the periphery thereof with a file surface 25 so as to make it a rotary file with which the finger nails can be conveniently filed by resting the ball of the finger on the handle and holding the edge of the nail against the rotating file. The nails may thus be quickly, easily and perfectly filed to any shape as the finger tip is at all times firmly supported on the handle portion surrounding the rotary file and can be evenly moved toward and away from the file. 30

Due to the fact that the shear plate of the 35 cutter head is rounded and the cutter operates on a radius, it is possible to tilt the shear plate and raise the cutter head from the surface of the skin at an angle thereto with the result that the hair may be cut at varying distances from 40 the skin.

We claim:

In a shaving machine, a handle, a cutter head comprising a fixed guard member, a movable guard member mounted to reciprocate on said 45 guard member, and a combined clamping screw and pressure member for clamping said guard member to said handle and holding said cutting member against said guard member.
